ABSTRACT: This invention relates to new and useful filament holding containers. More specifically, it is concerned with filament stock boxes which accept cut-to-length parallel synthetic filament in such a manner that picking devices can engage the filament at one end (longitudinal to the filament's length) and remove at least two prearranged filament tufts prior to insertion of said tufts into a brush construction.

NOVEL FILAMENT STOCK BOX

The need for improving filament stock boxes can be best illustrated by comparing and describing conventional filament stock boxes with the new and improved future-type filament stock boxes of this invention. The conventional staple-set brush picking operation employs a picker which can remove only one filament tuft at a time from a stock box or feed mechanism by first entering the stock box approximately at its midsection (lateral to the parallel filament) and picking a given amount of filament at the filament's midsection. Such filament stock boxes are disclosed in U.S. Pat. Nos. 2,433,191 (Baumgartner) and 3,059,972 (Schmidt). The picker then proceeds to transport the predetermined volume of parallel filament to a suitable means for doubling the filament at its midsection, just prior to stapling, thus resulting in a tuft having a U-shape wherein both ends of each individual filament are located at the working end of the resultant tuft. A staple or anchor of some sort is then inserted through the U-shape loop and the tuft forced into a predrilled hole in a brush back. Each tuft is formed in this manner, one after another, until the necessary number of filament tufts have been picked and stapled. The conventional filament stock box holds filament having a length double of that of the finished tuft. Also, the conventional stock box merely holds parallel filament and depends upon the picking wheel for removing a given amount of filament therefrom. In no way does the ordinary conventional filament stock box participate in forming: (1) tuft trim (2) tuft cross section (3) tuft diameter. Ordinary filament stock boxes can only contribute to the formation of one tuft at one time.

The filament stock boxes of this invention function on an entirely different principle. Said boxes are capable of dispensing two, three or any number of predetermined filament tufts simultaneously, in order that a brush construction containing all its filament tufts can be fabricated instantly. First, the filament employed for forming the tufts is half the length required for forming tufts in the conventional manner. In my U.S. Pat. No. 3,471,202, issued Oct. 7, 1969. I describe tuft-picking devices and tuft-forming units wherein brush construction containing tuft filaments are simultaneously picked and fabricated. The tuft picking devices described in that pending invention work in conjunction with the improved stock boxes of this invention, but the picking devices are not of concern in this instant invention. The picker or picking unit enters the filament stock box longitudinal to the filament's end and engages the filament from one end; at this instant, the filament tuft is formed and trimmed.

Secondly, in order to effect this operation it is necessary to provide means within the filament stock box for filament alignment and retention during the picking. Thirdly, it is necessary to provide means for retaining the unpicked filaments during tuft removal from the stock box and fourthly, means must be provided for allowing the reserve supply of filaments contained in the filament stock box to be moved into position for subsequent picking. Unlike conventional stock boxes, the new and improved filament stock box of this invention plays an integral part during tufted brush construction and formation, namely that of cooperating with the picking unit.

Objects and advantages of the invention will be set forth in part hereinafter and in part will be obvious herefrom, or may be learned by practice with the invention, the same being realized and attained by means of the combinations compositions and improvements pointed out in the appended claims.

The invention resides in the novel steps, methods, combinations, compositions and improvements herein shown and described.

The objects of this invention will now be described. While this invention is primarily concerned with new and novel filament stock boxes for dispensing synthetic filament for subsequent formation into tufted brushes, it should be realized that the principles of this invention are attained only through the novel combination of retaining cut-to-length parallel synthetic filament and dispensing those filaments in situations

wherein (1) single filament tufts are formed, (2) multiple filament tufts are formed, (3) complete tufted brush-type constructions are simultaneously formed and (4) continuous modular tufted strip-type brush constructions are formed.

5 It is therefore an object of this invention to provide new and novel and useful filament stock boxes for dispensing synthetic filament. Another object of this invention is to provide a filament-dispensing stock box wherein the length of the synthetic filament employed is approximately that of the length of the resultant filament tuft formed. A further object of this invention is to provide a filament-dispensing stock box wherein the resultant filament tufts so formed from the disposed filament are simultaneously removed from the stock box in the form of trimmed tufts.

10 15 A still further object of this invention is to provide a filament stock box having integral means for imparting filament alignment and retention during picking. Another object of this invention is to provide a filament stock box of the type set forth in the foregoing object wherein disposed cut-to-length synthetic filaments are picked simultaneously by employing a picking device which enters the filament stock box from the front through apertures and engages the filament at one end prior to removal. Yet still another object of this invention is to provide a filament-dispensing stock box having means for allowing a reserve supply of filaments to be aligned and positioned into the proper attitude for subsequent tuft formation.

20 25 Another object of this invention is to provide a filament dispensing stock box wherein at least two filament tufts having different tuft diameters are disposed simultaneously. Yet still another object of this invention is to provide a filament-dispensing stock box wherein at least two different filament tufts having different lengths are disposed simultaneously. Another object of this invention is to provide a filament stock 30 35 box wherein filament tufts having different colors are disposed simultaneously.

40 Further objects of this invention are to provide novel methods for the formation of synthetic filament tufts by employing the new and useful features of the types set forth in the foregoing objects.

45 The term "synthetic" filament as used hereinafter is to apply to those synthetic monofilaments which are formed from linear thermoplastic polymers from the group consisting of polystyrene and polystyrene copolymers, polyvinyl chloride and polyvinyl chloride-acetate copolymers, polyethylene, polypropylene, polyethylene-polypropylene copolymers, polyamides, polyamides, polyesters and polyurethane. Both oriented and unoriented monofilaments may be employed. Also, various cross-sectional shapes may be imparted to the monofilaments, such as for instance, i.e. circular, lobular, trifoliate, X and Y cross sections, triangular, polygonal, star, etc. Mixtures of synthetic monofilaments may be employed in cases where the compositions of the monofilaments are compatible during any fusing operations, i.e. heat sealing. Such filaments may have suitable crimp imparted to their length or a portion thereof.

50 55 The term "picking" as used in the specification refers to the formation of filament tufts wherein two or more tufts are formed simultaneously by engaging more than one cut-to-length filament by its end and removing same from a parallel disposed bundle of filaments. The picking devices employed are those types which are disclosed in the aforementioned mentioned U.S. Pat. No. 3,471,202.

60 65 The term "recess" as used in the specification refers to a recessed section contained on the inside back wall of the filament stock box which provides for holding the tuft ends in alignment during the picking operation. This recess is created by allowing a piston-type section of the wall to move (index) during the picking process.

70 75 The term "apertures" as used in the specification refers to an opening in the face of the stock box, said opening allowing entrance of the picker into the filament contained therein. The apertures correspond in dimension and shape to the cross section of the pickers.

IN THE DRAWING

FIG. 1 is a perspective view of the filament stock box of this invention.

FIG. 2 is a longitudinal section through a complete filament stock box, the section being along the line AA-AA in FIG. 1.

FIGS. 3, 4, 5 and 6 are respectively longitudinal sections through a complete filament stock box illustrating the functions of the working parts contained in the stock box.

FIGS. 7 and 8 are cross-sectional views illustrating an operational design for the recess piston of FIG. 2.

The filament stock box illustrated in FIG. 1 comprises a frame 1 in which the filament 6 is retained. The front of the filament stock box is provided with a movable aperture face 2, said face containing apertures 3. The aperture face is supported by rod 5 and is kept in an open attitude at all times, except during picking, by spring 4.

The filament stock box is further provided with a series of recess pistons which are housed in the element 12.

In order to fully illustrate the embodiments of this instant invention it is necessary to describe the different stages of operation, namely the picking operation relating to tuft formation, referring now to FIGS. 2, 3, 4, 5 and 6, by reference characters, the numeral 1 indicates generally the frame which supports cut-to-length synthetic filament and the various mechanisms which make up the stock box. The frame 1 consists of a four-sided box having a closed bottom and open top. There could be other modifications for the top and bottom, but for the sake of explanation, the detail shown in FIG. 1 will be considered. The front of the filament stock box contains an aperture face 2 containing aperture approaches 3, said aperture approaches being designed in such a fashion as to act as a guide means for aligning and allowing the tuft-forming pickers to pass therethrough during the picking operation. The aperture face is attached, but not fixed, to the front face of the filament stock box. Attached to and integral with the back of the frame is section 12 which contains the recess piston 9, its stop 10, and spring 11. The recess piston is so designed that except for picking, its face is flush with the back inside face of the stock box, thus allowing for free flow of the synthetic filament.

Referring specifically to FIG. 2, it can be shown that at the start of the picking operation, the following takes place: filament 6 is contained in a parallel relationship in frame 1 with its trim end oriented in the direction of the aperture face 2 while its butt end, or subsequent heat-sealed end, oriented in the direction of the recess piston 9. Tuft-forming pickers 8 contained in fixture 7 are lined up in direction B in such a manner as to allow entrance of the pickers 8 into the aperture approach 3 of the aperture face 2. Aperture face 2 is separated from frame 1 in order that the filament retention ring 13 can not come into contact with the filament 6. The recess piston is flush with the inside back wall of frame 1. By indexing fixture 7 of the tuft-forming device in direction B the front of pickers 8 first come in contact with the aperture approach 3 of the aperture face 2, and at the same instant, cause the aperture face 2 to close whereby the filament retention rings 13 are inserted into the filament 6. Referring to FIG. 3, it is shown that at this instant, the recess piston 9 has not been caused to move in direction B since pickers 8 have not as yet come into contact with filament 6.

Now referring to FIG. 4, as the fixture 7 of the tuft-forming device continues to move in direction B, the front tapered sections of pickers 8 become inserted into filament 6, thereby causing pressure in a longitudinal direct against the recess pistons 9, causing the pistons to retract in direction B, allowing the filament ends to move into the recess left by the recess pistons. By this action, the stops 10 are caused to resist pressure from spring 11.

When the entry of the pickers has been completed as in FIG. 5, the tuft-forming pickers 8 have been filled with the

required amount of filament for tuft formation. As the fixture 7 moves in reverse, direction C, the pickers 8 retain the filament tufts and as the pickers move through the aperture retaining rings 13 prevent unpicked filament 6 from being removed from the filament stock box. At this same instant recess pistons 9 are caused to move into a flush position with the inside back wall since springs 11 cause stop 10 to be moved forward. As the picking device 7 clears the aperture face, the aperture face then opens and is caused to move away a slight distance from the frame 1, as shown in FIG. 2. At this same instant, more filament 6 is caused to take the empty places left from the picking operation. Thus this process is repeated over and over again allowing filament to be picked simultaneously.

Referring to FIGS. 7 and 8, there is shown another form for the recess piston. In FIG. 7, the recess piston 9' is equipped with a filament retention ring 14 which allows the filament 6' above and below the ring to remain stationary during part of the picking operation. As the recess piston 9' retracts during tuft formation, the filament retention ring 14 does not in any way interfere with the operation, but serves more or less to confine the filament within the provided recess. This is shown in FIG. 8.

By providing a filament stock box with different distances between the front apertures and the flush recess piston face, it is possible to allow different lengths of cut-to-length synthetic filament to be accepted within the same filament stock box, thus resulting in simultaneously picking filament tufts of different lengths. Also, by providing partitions within the filament stock box, that is longitudinally and parallelly to the filament, it would be possible to form a series of filament tufts of more than one type and/or color simultaneously.

It should be understood that by providing apertures having different configurations, circular, square, triangular, etc., different tuft cross sections may be obtained. Likewise, by arranging the apertures within the aperture face, it is also possible to pick tuft configurations having unlimited geometric arrangements.

From the foregoing it will be apparent to those skilled in the art that the instant invention provides a very simple and effective filament stock box for accomplishing the objects of the invention.

The invention in its broader aspects is not limited to the specific steps, compositions, combinations and improvements described but departures may be made therefrom within the scope of the accompanying claims without departing from the principles of the invention and without sacrificing its chief advantages.

I claim:

1. A filament stock box for dispensing precut brush filaments comprising:
  - a. a frame having four sides and a bottom;
  - b. a housing element attached to said frame on a first side and containing a plurality of pistons having faces normally coplanar with the inside face of said first side; and
  - c. a movable aperture face resiliently mounted in spaced relation to an opening in a second side of said frame opposite said first side; said aperture face containing a plurality of apertures in the same configuration as said pistons, and each aperture being chamfered at the outer face of said plate; whereby said aperture face will be moved rearwardly as a picker element presses thereagainst and selected filament in the frame will depress said pistons.
2. A filament stock box as in claim 1 wherein the configuration of the apertures is that of the tuft configuration of a brush.
3. A filament stock box as in claim 2, wherein said plate has filament retention rings on its rearward face concentric with each aperture to separate the filament when the aperture face is moved rearwardly by a picker element.
